(57) **CLAIM**

I claim the ornamental design for a dispense cup, as shown and described.

DESCRIPTION

FIG. 1 is a perspective view of a dispense cup showing my new design;

FIG. 2 is a top view thereof;

FIG. 3 is a bottom view thereof;

FIG. 4 is a non-dispense side view thereof; and,

FIG. 5 is a dispense side view thereof.

The ornamental design which is claimed is shown in solid lines in the drawings.
